UNITED STATES PATENT OFFICE.

RICHARD E. KLINE, OF LOS ANGELES, CALIFORNIA, ASSIGNOR TO R. H. HERRON COMPANY, OF LOS ANGELES, CALIFORNIA, A CORPORATION OF CALIFORNIA.

PUMP.

1,147,248.

Specification of Letters Patent.

Patented July 20, 1915.

Application filed January 20, 1913. Serial No. 743,195.

To all whom it may concern:

Be it known that I, RICHARD E. KLINE, a citizen of the United States, residing at Los Angeles, State of California, have invented 5 new and useful Improvements in Pumps, of which the following is a specification.

This invention relates to an improved form of pump particularly adapted to situations where there is excessive wear on the 10 pump cylinder and piston.

In the practice of drilling wells with rotary rigs it is necessary to keep in constant circulation a suitable amount of water. This water rises in the well and carries out the 15 solid matter in the form of finely divided suspended particles. The muddy water is run through ditches and into a sump hole, allowing the larger part, the heavier portions, of the solid matter to settle. The water is then pumped back through the well; but it is neither practicable nor desirable to have the water perfectly clean. It is this 20 unclean water which causes very hard wear on the circulating pumps.

25 My invention seeks to obviate the inconvenience of having to constantly and repeatedly replace the wearing parts of the pump piston.

My invention consists fundamentally in 30 the provision of a suitable packing means on the pump piston capable of gradual expansion by adjustment from time to time. The preferred form includes an expansible split sleeve, around which the packing is 35 arranged; in combination with an easily operated means for expanding the sleeve. I provide that the expansive adjustment may be effected by the removal of a small cover plate on the cylinder head and by the adjustment of a single screw and lock nut. Complete renewal is needed only at long intervals—many times the life of the arrangement outwardly in use.

40 I have shown a preferred form of my invention in the accompanying drawings, in which:

Figure 1 is a longitudinal central section showing my invention and its application. Fig. 2 is a cross section taken on two different planes, as indicated by line 2—2 of Fig. 1. Fig. 3 is a perspective showing a modified means for expanding the split sleeve.

In the drawings, 10 designates any ordinary cylinder which may have a cylinder head 11 preferably provided with a small

opening 12 and a cover plate 13. Whenever it is desired to adjust the piston packing, this cover plate 13 is only required to be removed; thus obviating the inconvenience of removing the whole cylinder head.

My improved piston is mounted upon the piston rod 14; this rod having a portion 14^a which is exteriorly tapered and has a central longitudinal bore 15. Upon the tapered portion of the rod there is mounted a member 16, consisting in a sleeve 17 and an end disk or head 18. Another end disk or head 19 is mounted at the end of the sleeve 17, the sleeve 17 becoming a spacer between the two heads. A nut 20 holds all these parts on the rod portion 14^a. The head 18 is integral with the sleeve 17; and the head 19 fits on the portion 14^a of piston rod 14 against sleeve 17. This construction provides for easy removal and renewal of the heads without removal of the other parts; and also provides for standardization of parts of the piston.

In the space between the two piston heads 18 and 19 and around the sleeve 17 there is 45 arranged an expansible sleeve 20 preferably composed of a plurality of segments 21 of any suitable number. Each of these segments is mounted upon guide rods 22, the guide rods projecting radially through the 50 sleeve 17 and through the piston rod 14^a and into the interior bore 15 of the rod.

The packing 25 is of any suitable character and quality, preferably square in cross sections, arranged in a number of circles 55 with butted ends around the expansible sleeve 20. The breaks in the packing at the butted ends are arranged so as to not come opposite each other. The packing is placed around the piston construction and the piston heads 18 and 19 are then forced toward each other to compress the packing between them, thus making a liquid tight mass of packing between the two heads. The size of the packing when new is such that it will 60 engage the cylinder walls with the expansible sleeve 20 in its contracted position.

As wear takes place on the packing, the segments of the expansible sleeve are moved 65 radially outwardly by a means acting upon the inner ends of the guide rods 22. This means comprises a member 30 having thereon two wedge portions 31 engaging with the guide rods 22. The member 30 is of such size as to fit in the bore 15; and its longitu- 70

dinal movement in the bore will cause or allow the movement of the guide rods 22. Movement of member 30 to the right in Fig. 1 will cause outward movement of the guide rods and cause expansion of the sleeve 20 and of the packing, keeping the packing always truly circular and in good contact with the cylinder. Movement of member 30 is accomplished by means of a screw 32 co-
 5 operating with the screw threaded portion 33 of bore 15. The outer end of the screw 32 has a square wrench opening 34; and a lock nut 35 suffices to hold the screw in any desired position. This lock nut also over-
 10 hangs the nut 20 and locks it securely in position.

The wedge member 30 may either be circular in cross section, as is illustrated in Fig. 1, or may be square as is shown in Fig. 3. 20 The circular wedge member may or may not be swivelly attached to the adjusting screw 32; but the square wedge member will be attached only by swivel. The square member has the advantage that the engagement 25 of the ends of rods 22 with its wedge faces prevent its rotation; but, on the other hand, the circular wedge member is more easily manufactured and is very efficient in use.

With my construction, wear on the piston 30 packing may be taken up from time to time by the simple and quick operation of adjusting the screw 32. For this purpose it is only necessary to remove the cover plate 13, loosen the lock nut 35 and then turn the screw 32 35 as much as desired. A slight adjustment from time to time suffices to keep the piston in working order; and it is only after the packing 25 is completely worn out that it becomes necessary to loosen the piston head 40 19 and renew the packing. Even this renewal is easily slid out of the cylinder as the packing is put into place.

As hereinbefore stated, my invention is particularly adapted for use where the liquid to be pumped contains abrasive matter which causes great wear on the piston. Although I have devised my invention with a view to providing a circulating pump for

rotary drilling rigs, I do not wish to limit myself to this particular use; nor do I wish 50 to limit myself to the specific details herein described, reserving the right to make such minor changes as may appear advantageous to adapt my invention to various combinations and conditions. The feature I wish to 55 particularly emphasize is the use of the hollow piston rod with the expanding means arranged around and within it.

I have shown a coil of spring 50 which surrounds the members 20 for the purpose of 60 bringing the members back to their normal position when the device is contracted. This spring is comparatively small and in no way interferes with the packing placed over it.

Having described my invention I claim: 65

In combination with a cylinder, a piston rod having a longitudinal bore leading from one end, a piston on said end of the piston rod comprising a pair of heads, a sleeve integral with one of the heads fitting around 70 the piston rod and between the heads and forming a spacer between them, the sleeve and its attached head having a taper fit on the piston rod, a nut on the end of the piston rod to hold the two heads and the sleeve on 75 the rod, a plurality of loose cylindrical segments around the sleeve between the two heads, guide rods attached to each segment projecting inwardly through the sleeve and the piston rod into the longitudinal bore 80 thereof, a spring surrounding the segments to contract them, expansible packing surrounding the spring and segments between the two heads, a longitudinal slidible wedge member in the bore of the piston rod, a bolt 85 screw threaded into the end of the piston rod connected to the wedge member, and means to lock said bolt in any set position, substantially as described.

In witness that I claim the foregoing I 90 have hereunto subscribed my name this 4th day of January, 1913.

RICHARD E. KLINE.
